C. F. STODDARD

PNEUMATIC VALVE MECHANISM

Filed April 25, 1925

UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

PNEUMATIC-VALVE MECHANISM.

Application filed April 25, 1925. Serial No. 25,725.

This invention relates to valve mechanisms particularly adapted for use in automatic musical instruments.

It is an object of this invention to provide a valve mechanism which shall operate noiselessly, but which shall at the same time be of large capacity,—that is, it shall have the ability to pass relatively large quantities of air with great rapidity. It is a further object of the invention to provide means whereby said valve mechanism may be operated automatically from the tracker bar.

Other objects and advantages of the invention will appear hereinafter.

15 The single figure of the drawing illustrates semi-diagrammatically a preferred embodiment of the invention selected for purposes of illustration.

Referring to the drawing the valve block 20 1 is provided with a chamber 2 having a conduit 3 leading to any suitable source of pneumatic exhaust. Located in the upper part 25 of the chamber 2 is a cylindrical member 4 having a partition 5 arranged at the upper end thereof, said partition being provided with a plurality of perforations 6 to permit substantially free passage of air therethrough. Above the cylindrical member 4 and arranged to cover the partition 5 and 30 the perforations 6 therein is a diaphragm 7, above which is a diaphragm chamber 8.

The chamber 2 is connected by means of a duct 9 and connecting duct 10 with the exhaust chamber 11 of the inside valve 12. 35 The diaphragm chamber 13 of this valve is also connected by means of duct 14 and the duct 9 to the chamber 2, a suitable bleed cup 15 being interposed in the duct 14.

The valve block 1 is also provided with a 40 chamber 16 connected by means of a port 17 with a pneumatic 18 or other device, the operation of which is to be controlled by the valve mechanism. When the diaphragm 7 is seated, covering the perforations 6 of the 45 partition 5, passage of air between the chambers 16 and 2 is prevented, but when the diaphragm 7 is raised as hereinafter explained, air is drawn from the chamber 16 through the perforations 6, chamber 2, and 50 conduit 3 to the source of exhaust.

The diaphragm chamber 13 of the valve 12 is provided with a duct 19 leading to a suitable opening of the usual tracker bar 19' of the instrument. If desired, a lock valve 55 mechanism of any suitable construction such,

for instance, as illustrated in prior Patent No. 1,409,492, patented March 14, 1922, may be interposed between the duct 19 and the tracker bar in order that short perforations of a note sheet may be employed to control the operation of the valve mechanism.

In the normal course of operation, when the exhaust apparatus of the piano is started, the chamber 2 is subjected to exhaust. The chambers 11 and 13 of the valve 12 are also 60 subjected to exhaust through the ducts 9, 10, and 14, and since the same degree of exhaust is maintained in both of the chambers 11 and 13, the valve 12 remains seated and atmosphere is permitted to pass through the port 70 20 and duct 21 to the diaphragm chamber 8. The differential of pressure thus created between the atmosphere in diaphragm chamber 8 and the tension in chamber 2 causes the diaphragm 7 to seat tightly against the partition 5, sealing the perforations 6 to prevent the passage of air therethrough.

If under these conditions, a perforation in the note sheet crosses the tracker bar opening, atmosphere is admitted to the diaphragm chamber 13 through the tracker duct 19 more rapidly than it can be withdrawn through the bleed 15. A pressure differential is created thereby which causes the valve 12 to rise to close the port 20 to atmosphere and to open the port 22 to the exhaust chamber 11. The diaphragm chamber 8 is thereby subjected to exhaust through the duct 21 and pneumatic forces acting on the opposite sides of that part of the diaphragm 7 covering the partition 5 and the perforations 6 are equalized. The remainder of the diaphragm 7, however, is subjected to exhaust on its upper side and to 80 atmosphere from the chamber 16 on its lower side. This pressure differential immediately causes the edge of the diaphragm 7 to peel away from the partition 5 to open the perforations 6, thus permitting air to be withdrawn from the chamber 16, the partition 5 serving as a bearing surface for said diaphragm from which it may roll as it is influenced by pneumatic forces. As soon 85 as the air has been exhausted from the chamber 16 sufficiently to equalize the pressures existing in the three chambers 2, 8 and 16, the diaphragm 7 returns to its seat under the influence of the light spring 7'. This spring 90 may be located in the chamber 8 and operates to return the diaphragm to its seat and 95

110

The diaphragm chamber 13 of the valve 12 is provided with a duct 19 leading to a suitable opening of the usual tracker bar 19' of the instrument. If desired, a lock valve 55 mechanism of any suitable construction such,

to hold it thereon except when raised under the influence of pneumatic forces as herein explained.

At the other end of the valve block 1 is arranged a cylindrical member 23 opening into the chamber 16 and having a partition 24 provided with a plurality of perforations 25 arranged at the upper end thereof similarly to the parts 4, 5 and 6 previously described. Above the cylindrical member 23 and arranged to cover the partition 24 and perforations 25 is a diaphragm 26 above which is a diaphragm chamber 27. The diaphragm chamber communicates through the duct 28 with the valve chamber 29 of the inside valve 30. Chamber 31 beneath the valve 30 is connected by means of the duct 32 with the chamber 16, while chamber 33 is connected by means of the duct 34 with the chamber controlled by the valve 12.

Whenever the valve 12 is raised, as previously described, the chamber 33 of the valve 30 is subjected immediately to exhaust through the duct 34 while the chamber 31 is more gradually exhausted as the chamber 16 is exhausted due to the lifting of the diaphragm 7. Pressures are thus eventually equalized in chambers 31 and 33 but the valve 30 remains seated for prior to equalization the pressure in chamber 31 is greater than in chamber 33. So long as pressures in the chambers 31 and 33 are thus equalized, valve 30 remains seated and is unaffected by the admission of atmosphere to the tracker duct 19. Thus, under normal conditions, or during operation of the diaphragm 7, valve 30 remains seated and atmosphere is admitted through the port 35 and duct 28 to the diaphragm chamber 27. If chamber 16 is at atmospheric pressure, the entire area of diaphragm 26 is subjected to atmospheric pressure and the diaphragm will be pressed into contact with the partition 24 by the light spring 36'. Whenever the chamber 16 is subjected to exhaust, a differential of pressure is created on that part of the diaphragm lying above the partition 24 and perforations 25 which holds it more tightly against the partition 24 thereby preventing the passage of air therethrough.

If, under these conditions, the tracker duct 19 is closed to atmosphere, pressures in the chambers 11 and 13 are equalized and the valve 12 returns to its seat admitting atmosphere through the port 20 and duct 21 to the diaphragm chamber 8, the differential of pressure between the chambers 8 and 2 pressing the diaphragm against the partition 5 so as to seal the perforations 6. At the same time atmosphere is admitted through the port 20 and duct 34 to the diaphragm chamber 33, causing the valve 30 to rise to close the port 35 to atmosphere, and opening the port 36 to the tension which at the time exists in chamber 16. The dia-

phragm chamber 27 is thereby exhausted and pressures acting on that part of the diaphragm covering the partition 24 and the perforations 25 are equalized. The remaining portion of the diaphragm, however, is subjected to the pressure differential between tension in the chamber 27 and atmosphere in the chamber 37 whereby the diaphragm 26 is caused to peel away from the partition 24 to permit atmosphere to enter through the perforations 25 to relieve the exhaust existing in chamber 16. As soon as the chamber 16 reaches atmospheric pressure, diaphragm 26 returns to its seat under the influence of spring 36'. Valve 30 likewise returns to its seat by gravity since both of the chambers 31 and 33 are subjected to atmospheric pressure.

It will be observed that during the latter part of the operation just described, it is the tension existing in the chamber 16 and pneumatic 18 which serves as the motive force to operate the valves to admit atmosphere to the chamber and pneumatic to relieve the tension therein. Indeed it is the tension generated by the expansion of the pneumatic under the weight of the sticker 18' and attached parts which lifts the diaphragm 26 and keeps it lifted during the period during which atmosphere is being admitted to the chamber 16 and pneumatic 18.

The valve mechanism described may be useful in various parts of mechanisms for operating musical instruments automatically. It has been found particularly useful for controlling the operation of pedal pneumatics where it is desired to collapse a pneumatic of relatively large size with great rapidity. Heretofore it has been difficult to collapse such pneumatic rapidly without producing undesirable noises, for valves of the usual construction traveling from one seat to another, and having sufficient capacity to collapse the pneumatic rapidly were found to cause a slapping noise as they reached the opposite seat, and a lisping sound during transit from one seat to another. In the present construction it will be observed that due to the large capacity of the ports formed by the perforations 6 and 25, an actuated pneumatic may collapse and expand with great rapidity. Due to the construction and operation of the diaphragms controlling the ports, however, no undesirable noise is produced because the diaphragm is merely rolled off its seat and does not strike against another seat. In addition it returns to its seat under conditions wherein the pneumatic forces acting upon the diaphragm are substantially equalized and the diaphragm therefore in effect merely settles back onto the seat under the influence of its own weight and the force of the light springs 7' and 36'.

It will be understood that the invention

may be variously modified and embodied within the scope of the subjoined claims.

I claim as my invention:

1. In a pneumatic valve action, in combination, means for connection to a source of exhaust, means for connection to an actuated pneumatic, and means including a valve for controlling the application of exhaust to said pneumatic, said last-named means being adapted to cause said valve to open to collapse said pneumatic and to automatically close when said pneumatic is completely collapsed.
2. In a pneumatic valve action, in combination, means for connection to a source of exhaust, means for connection to an actuated pneumatic, and means including a valve for controlling the application of exhaust to said pneumatic, said last-named means being adapted to cause said valve to open to collapse said pneumatic and to automatically close when said pneumatic is completely collapsed, and separate means for controlling the admission of atmosphere to said pneumatic to expand the same.
3. In a pneumatic valve action, in combination, means for connection to a source of exhaust, means for connection to an actuated pneumatic, and means including a valve for controlling the application of exhaust to said pneumatic, said last-named means being adapted to cause said valve to open to collapse said pneumatic and to automatically close when said pneumatic is completely collapsed, separate means for controlling the admission of atmosphere to said pneumatic to expand the same, and means to control both of said means from a single tracker bar opening.
4. In a pneumatic valve action, in combination, means for connection to a source of exhaust, means for connection to an actuated pneumatic, means including a valve for controlling the application of exhaust to said pneumatic, said last-named means being adapted to cause said valve to open to collapse said pneumatic, and to automatically close when said pneumatic is completely collapsed, separate means including a valve for controlling the admission of atmosphere to said pneumatic to expand the same, said separate means being adapted to cause said included valve to open to admit atmosphere to expand said pneumatic and to automatically close when said pneumatic is completely expanded.
5. In a pneumatic valve action, in combination, means for connecting to a source of exhaust, means for connection to an actuated pneumatic, means including a valve for controlling the application of exhaust to said pneumatic, said last-named means being adapted to cause said valve to open to collapse said pneumatic, and to automatically close when said pneumatic is completely collapsed.

completely collapsed, separate means including a valve for controlling the admission of atmosphere to said pneumatic to expand the same, said means being adapted to cause said valve to open to admit atmosphere to expand said pneumatic and to automatically close when said pneumatic is completely expanded, and means to control both of said controlling means from a single tracker bar opening.

6. In a pneumatic valve action, in combination, means for connection to a source of exhaust, means for connection to an actuated pneumatic, and means including a diaphragm and cooperating port for controlling the application of exhaust to said pneumatic, said diaphragm being influenced and operated by opposed pneumatic forces, and means for causing a sudden large differential in said forces to cause said diaphragm to open said port to collapse said pneumatic, and for permitting said forces to become equalized when said pneumatic is completely collapsed whereby said valve closes automatically.

7. In a valve mechanism having a chamber connected with a source of exhaust and a second chamber to be exhausted, a valve actuated by the exhaust in said first chamber for controlling communication between said chambers whereby said second chamber may be exhausted, and a second valve actuated by the residual tension in said second chamber for controlling communication between said chamber and atmosphere.

8. In a pneumatic valve action, in combination, means for connection to a source of exhaust, means for connection to an actuated pneumatic, means including a valve actuated by said exhaust for controlling communication between said source of exhaust and said actuated pneumatic to collapse the same, and means including a second valve actuated by the exhaust generated by the expansion of said actuated pneumatic for controlling communication between said pneumatic and atmosphere.

9. In a pneumatic valve mechanism, in combination, a chamber connected with a source of exhaust, a second chamber to be exhausted, a third chamber, a valve for controlling communication between said first and second chambers, said valve being influenced by the pneumatic condition existing in each of said chambers, and means including a valve for connecting said third chamber selectively to either atmosphere or to said first chamber.

10. In a pneumatic valve mechanism, in combination, a chamber connected with a source of exhaust, a second chamber to be exhausted, a third chamber, a diaphragm for controlling communication between said first and second chambers, said diaphragm being influenced by the pneumatic condition

existing in each of said chambers, and means including a valve for connecting said third chamber selectively to either atmosphere or to said first chamber.

- 5 11. In a pneumatic valve mechanism, in combination, a chamber connected with a source of exhaust, a second chamber to be exhausted, a third chamber, a valve for controlling communication between said first and second chambers, said valve being influenced by the pneumatic condition existing in each of said chambers, a tracker and tracker controlled means for connecting said third chamber selectively to either atmosphere or to said first chamber.

- 10 12. In a pneumatic valve mechanism, in combination, a chamber connected with a source of exhaust, a second chamber to be exhausted, a third chamber, a diaphragm for controlling communication between said first and second chambers, said diaphragm being influenced by the pneumatic condition existing in each of said chambers, a tracker and tracker controlled means for connecting said third chamber selectively to either atmosphere or to said first chamber.

- 15 13. In a pneumatic valve mechanism, in

combination, a chamber connected with an actuated pneumatic, a second chamber having constant communication with atmosphere, a third chamber, a valve for controlling communication between said first and second chambers, said valve being influenced by the pneumatic condition existing in each of said chambers, and means including a valve for connecting said third chamber selectively to either atmosphere or to said first chamber.

20 14. In a pneumatic valve mechanism, in combination, a chamber connected with an actuated pneumatic, a second chamber having constant communication with atmosphere, a third chamber, a valve for controlling communication between said first and second chambers, said valve being influenced by the pneumatic condition existing in each of said chambers, a tracker and tracker controlled means for connecting said third chamber selectively to either atmosphere or to said first chamber.

25 In testimony whereof, I have signed my name to this specification this 23rd day of April, 1925.

CHARLES F. STODDARD.
